(57) **CLAIM**

The ornamental design for a map utilization assistance tool, as shown and described.

DESCRIPTION

FIG. 1 is a perspective view of the map utilization assistance tool.

FIG. 2 is a front elevation view of the invention.

FIG. 3 is a first side view of the invention, the opposite side view being a mirror image.

FIG. 4 is a second side view of the invention, the opposite side being a mirror image.

FIG. 5 is a rear elevation view of the invention.

FIG. 6 is a detail of that indicated in FIG. 3; and,

FIG. 7 is a perspective view of the invention in use with the slides extended.

The broken lines in FIGS. 1–4, 6 and 7 are for purposes of illustration only and form no part of the claimed design.
